UNITED STATES PATENT OFFICE.

ORRIN MILO WHITMAN, OF BOSTON, MASSACHUSETTS.

REFRIGERATOR.

SPECIFICATION forming part of Letters Patent No. 337,909, dated March 16, 1886.

Application filed October 19, 1885. Serial No. 180,271. (No model.)

To all whom it may concern:

Be it known that I, ORRIN MILO WHITMAN, of Boston, in the county of Suffolk, of the Commonwealth of Massachusetts, have invented a new and useful Improvement in Refrigerators; and I do hereby declare the same to be described in the following specification and represented in the accompanying drawings, of which—

10 Figure 1 is a front elevation, Fig. 2 a transverse and median section, Fig. 3 a horizontal section, and Fig. 4 an end elevation, of a refrigerator containing my invention, the nature of which is defined in the claims hereinafter presented. Fig. 5 is an end view of one of the butter-firkin-holding chambers as open, the chamber represented in Fig. 2 being shown as closed.

In the said drawings, A denotes the case of the refrigerator, it having in its upper part a chamber, B, for holding ice. This chamber extends from one to the other end of the case, and is provided at one of such ends with an opening, a, and a door, b, thereto, (see Fig. 4,) such opening being for the admission of ice into the chamber. Immediately below the said ice chamber or receptacle there is a series of separate chambers, C, each of which has in its front an opening, c, provided with 25 a door, D, that is pivoted so as to be capable of being turned upward to close the opening, or downward into an inclined position, so as to uncover the opening. From this door two racks, d, project into the chamber of such door, such racks being for a bar, e, laid in them. On this bar and against the door is a butter-firkin, E, or other vessel for holding the material or liquid, whether it be butter, milk, or other matter or matters, to be kept cool.

40 Through the bottom of each chamber C there is an opening, f, provided with a valve or door, g, that is hinged to such bottom, and there is also in the top of the chamber another opening, h, provided with a door, i. The space k' directly over such opening h freely communicates with the upper part of the ice-receptacle. The door i, hinged at its rear, has an arm, k, projecting from it and connected 45 to one of the racks by a cord or wire, l, such rack being also connected with the lower

door, g, by a cord or wire, m, which may be either elastic or inelastic, lengthwise of it.

When the door D of the chamber is closed, both of the doors or valves g and i will be open, 55 as represented in Fig. 2, and cool air from the ice-receptacle will flow freely through the chamber C; but when the door D is open and inclined, as shown in Fig. 5, both of the doors or valves g and i will be in position to close 60 their openings, so as to prevent cool air from escaping from the case through the chamber C of such door D.

In rear of the ice-receptacle is a passage, n, for the air to pass from the space o over the 65 said receptacle into the chamber or space p below the several chambers C, such space p being for holding matters to be kept cool. In the front of the case is a doorway, q, opening into the chamber or space p, such doorway being provided with a door or doors, r, for closing it.

When either door D is opened into an inclined position, the firkin, tub, or vessel resting against it will be tipped into a like position, so as to enable its cover to be removed, and the contents to be exposed and access thereto to be had. Should the vessel be a jug holding a liquid, the door, with such jug resting on it, may be turned into an inclined position for the liquid to escape from it into a pan or receptacle. From the above it will be seen that to obtain any part of the contents of the jug or firkin there will be no necessity of removing such jug or firkin from the chamber or its door.

A refrigerator thus made is highly useful for keeping butter, cream, or milk in a cool state. The racks projecting from each door D enable their bar to be adjusted in them as 90 the length of the firkin or vessel supported on it may require in order to bring the top or cover of the said firkin or vessel to its proper altitude relatively to the top of the door.

I do not claim a counter provided with a 95 series of bins adapted to fit in recesses in such counter and provided with trunnions to enter curved grooves, all as shown in the United States Patent No. 222,816. Nor do I claim a kitchen-cabinet provided with such bins, as 100 represented in the United States Patent No. 209,936. Nor do I claim a refrigerator pro-

vided with drawers, each of whose fronts is hinged or applied so as to be capable of being turned from a vertical down into a horizontal position, as shown in the United States Patent 5 No. 78,308. Nor do I claim a refrigerator constructed as represented in the United States Patent No. 265,202, in which the door is pivoted so as to swing horizontally, but has projecting from it no devices for supporting a 10 firkin or vessel, so as to swing outwardly with the door.

I claim—

1. The refrigerator constructed substantially as described—viz., with the ice-receptacle B 15 in its upper portion, the chamber p in its lower part, one or more intermediate chambers, C, a doorway to each of such chambers, and a door, D, thereto, pivoted so as to be capable of being turned outwardly and down- 20 wardly, as set forth, racks or devices in such door for sustaining a bar for supporting a firkin or other vessel, openings in the top and bottom of the chamber C, and to each of such 25 openings a valve so connected with the door that on such door being opened and turned

outwardly and downwardly into an inclined position both of such openings should be closed, but be open when the door is closed, all as set forth.

2. The combination, with a refrigerator having to each of its cooling-chambers a door to open outwardly and downward as explained, of the racks projecting inwardly from such door and serving to support a bar for sustaining a firkin or vessel arranged with such 35 door, as specified.

3. A refrigerator having one or more cooling-chambers and to each a door pivoted to open downward into an inclined position and provided with a device or means for supporting a firkin or other vessel to enable it to be moved by such door from its position within the chamber down into an inclined position, all being substantially and for the purpose as set forth.

ORRIN MILO WHITMAN.
